UNITED STATES PATENT OFFICE.

CARROLL E. MILLER, JR., OF SAN FRANCISCO, CALIFORNIA.

DESIGN FOR A RING.

Application filed July 3, 1922. Serial No. 2,939. Term of patent 3½ years.

To all whom it may concern:

Be it known that I, CARROLL E. MILLER, Jr., a citizen of the United States of America, residing at San Francisco, in the county of San Francisco and State of California, have invented a new, original, and ornamental Design for a Ring, of which the following is a specification, reference being had to the accompanying drawing, forming a part thereof.

Figure 1 is a side elevation of a finger ring showing my design,

Figure 2 is an edge elevation of the same,

Figure 3 is a top plan view of the design. From an inspection of the figures, it will be seen that the design comprises a ring exteriorly embossed with characters, said ring having pivotally secured therein a panel showing the emblem of the Order of the Mystic Shriners on one surface, and an insert of jade on the opposite surface.

I claim:—

The ornamental design for a ring, as shown and described.

CARROLL E. MILLER, JR.
